[57] CLAIM

The ornamental design for a transaction terminal console, as shown and described.

DESCRIPTION

FIG. 1 is a perspective view of a transaction terminal console showing my new design;

FIG. 2 is a top plan view of the transaction terminal console shown in FIG. 1;

FIG. 3 is a right side elevational view of the transaction terminal console shown in FIG. 1;

FIG. 4 is a left side elevational view of the transaction terminal console shown in FIG. 1;

FIG. 5 is a front elevational view of the transaction terminal console shown in FIG. 1; and,

FIG. 6 is a back elevational view of the transaction terminal console shown in FIG. 1.

The bottom side of the transaction terminal console is unornamented and forms no part of my invention.
